UNITED STATES PATENT OFFICE.

EARL H. RICHARDSON, OF ONTARIO, CALIFORNIA, ASSIGNOR TO EDISON ELECTRIC APPLIANCE COMPANY, INC., A CORPORATION OF NEW YORK.

ELECTRICALLY-HEATED DEVICE.

Application filed February 21, 1921. Serial No. 446,618.

To all whom it may concern:

Be it known that I, EARL H. RICHARDSON, a citizen of the United States, residing at Ontario, in the county of San Bernardino, 5 State of California, have invented certain new and useful Improvements in Electrically-Heated Devices, of which the following is a specification.

My invention relates to electrically heated 10 devices and more particularly to means for protecting such devices from overheating. My improved arrangement is particularly applicable to electrically heated flat irons, although it is not necessarily limited to this 15 application.

In carrying out my present invention, I employ the ratchet or toothed-wheel arrangement disclosed in my previous Patent No. 937,332, dated Oct. 19, 1909. In the 20 arrangement of said patent the ratchet wheel is normally held stationary by a fusible metal which melts at the temperature at which the device is to operate and allows the ratchet wheel to turn and open 25 the heating circuit. While I have illustrated my present device in connection with a fusible metal for anchoring the ratchet wheel, my invention in its broad aspect is not limited to this particular arrangement.

30 One of the important features of my invention is the provision of a simple and efficient arrangement cooperating with the normally stationary ratchet wheel whereby, when a predetermined temperature is 35 reached, the circuit is opened with a quick-break action, and when the flat iron or other electrically heated device cools off sufficiently, the switch may be closed manually with a snap action. The arrangement 40 is such that the parts, including the spring which causes the snap action, are unaffected by the temperature at which the device is operated. I have also provided a fusible metal which is practically free from 45 oxidation due to repeated melting and solidifying. This improved fusible metal, which is in fact an alloy, forms an important part of my present invention.

In the accompanying drawings illustrating 50 one embodiment of my invention, Fig. 1 is a side elevation of a flat iron incorporating my improvements, partially broken away to show the construction; Fig. 2 is a

plan view with the cover removed to show the switch mechanism; Fig. 3 shows an enlarged view of the switch mechanism; Fig. 4 is a detail of the contact member of the switch, and Fig. 5 is a plan view of the same.

Referring to the drawings it will be seen 60 that I have shown my invention in connection with a standard form of flat iron consisting of a sole plate 10 and a storage plate 11, the heating unit 12 being mounted between these two plates which are pressed together by the screw 13. The cover 14 has an enlargement at 15 to take care of the added depth required by the switch mechanism. The numeral 16 indicates a well formed in the sole plate for containing the 70 fusible metal or alloy 17. A vertical shaft 18, having its lower bearing in the bottom of the well at 19, extends upward through an opening in the plate 11 and is provided at its upper end with a toothed or ratchet 75 wheel 20 rigidly fastened to the shaft. The lower end of the shaft which is embedded in the fusible metal is provided with anchoring projections 21.

The switch mechanism cooperating with 80 the ratchet wheel 20 is clearly illustrated in Fig. 3. It consists of a supporting plate 22, upon which is mounted a stationary bracket consisting of a flanged base 23 secured to the plate 22 and the two outwardly projecting wing portions 24 and 25 which are 85 above and spaced from the plate 22. Pivotally mounted between the wing 25 of this bracket and the plate 22 is a switch member 26 which is in the form of a rectangle 90 with one side removed. This switch member has a projection in the form of a knife edge 27 which has a bearing in a triangular slot in wing 25 and another projection having a similar bearing directly underneath 95 in the plate 22. This switch member is indicated in detail in Figs. 4 and 5, in which the bridging member 26' which cooperates with stationary contacts 27' is shown mounted on member 26 so as to be insulated 100 therefrom, through the agency of a clamp 28' having a loop portion which loosely supports member 26' to allow for self adjustment of the contacts when the switch is closed. The operating member for the 105 switch is indicated by the numeral 28. This

member is channel-shaped, as shown, and has at one end a knife-edge bearing at 29 in wing 24 and a similar bearing directly underneath it in the plate 22. The other 5 end of this member is provided with a hook 30 which is connected by a link 31 with an S-shaped member 32. This link 31 is Z-shaped and pivoted to hook 30 on ears 31', the lower portion forming a pawl 29' as 10 shown. The lower end of the S-shaped member is connected with the switch member 26 by a link 33, while the upper end is connected with a spring 34 by a link 35. This spring, which is of ample proportions 15 and contains several coils, is adjustably secured to the plate 22 by being mounted in lugs 22' on a rotatable plate 23' of the form shown in dotted lines, the lugs projecting through slots in plate 22. This plate 23' is 20 provided with upwardly projecting lugs 36 which embrace the cam shaped edge 37 of the plate 22. This rotatable plate is provided with a projection 38 for turning the plate and thereby turning the end of the 25 spring to change the tension. The outline of the portion 37 of the plate 22 is cam shaped so that when the plate is placed in the proper position by the projection 38 to give the desired tension, the projections 36, 30 being forced in against the cam surface, will hold the plate in position. The free end of the spring extends to the right and engages a slot in the link 35, which link passes through a slot in the link 33 and also 35 through a slot in the member 28. Looking at Fig. 3 therefore, the spring pulls down on the link 35, thereby giving the S-shaped member 32 a tendency to rotate in a counter-clockwise direction. This, therefore, 40 gives the link 33 a tendency to move to the right. When, therefore, the point of support 33' for the link 33 is above the knife edge 27, the spring, acting through the S-shaped member 32 and link 33, will force 45 the switch member 26 upward to closed position, whereas when the point of support 33' passes below the knife edge 27, the switch member may be forced downward to open position. This gives a snap action in 50 both directions, as will be well understood. The pawl 29' forming a part of link 31 and engaging the teeth of the ratchet wheel 20, is, therefore, forced inward against the ratchet teeth by the spring 34, since the link 55 31, which is in one piece with the pawl, is forced downward by the spring through the link 35. An operating knob or button 39 is pivoted to the operating member 28 at 40 so as to have a slight motion to adjust it 60 self in its various positions. A stop 41 limits the downward movement of the operating member 28. This button 39 projects through the casing 15 so that it may be operated manually. When the switch is automatically opened, the button projects out-

ward some distance so that the operator may see that the switch is open. To close the switch it is only necessary to press this button inward. The stationary contacts at 70 27' are connected in the circuit of the heating element as indicated, so that when these contacts are not bridged by the member 26' the circuit to the heating element will be open.

The fusible alloy 17 employed in the well 75 16 is one which I have found in practice to be practically non-oxidizable. One of the principal difficulties met with in devices depending upon a fusible metal for their action is that the metal, in time, will oxidize due to repeated melting and solidifying and will become ineffective. I have produced an alloy, however, in which oxidization does not occur, at least within practical limits. The alloy which I have found to be very serviceable is composed of 90% zinc, 4% bismuth and 6% aluminum, and I have found that these metals should be as nearly pure as possible in order to obtain the best results. The melting point of this alloy is about 80 750° F., and is practically constant in the transition from the solid to the liquid state, and vice versa. Its characteristics do not change after repeated melting and solidifying. 85 90 95

As thus constructed and arranged the operation of my device is as follows:

In Fig. 2 the parts are in the position in which they are left when the switch has automatically opened. Assuming that the iron 100 has cooled off sufficiently so that the fusible metal has solidified, the ratchet wheel 20 will be held stationary. In order to close the switch now, the operator pushes on the button 39 which projects through the casing 105 15, until the end is practically flush with the casing. In doing this the pawl 29' passes over the teeth of the ratchet 20 as the member 28 is moved inward. As this member 28 moves inward, carrying with it the 110 S-shaped member 32 and the links attached thereto, the link 33 passes above the knife edge 27 so that the pull on the link 33 will now cause a turning movement of the switch member 26 around the knife edge 27 to close 115 the switch. The switch will therefore close to the position shown in Fig. 3 with a snap action and the pawl 29' engaging with the teeth of the ratchet 20 will hold it in this 120 position. Assuming now that the iron is in operation and that it reaches a temperature of approximately 750° F., the fusible alloy 17 in the well 16 will melt, thereby allowing the shaft 18 carrying the ratchet wheel 20 to turn. Since the wheel 20 no longer 125 holds the switch parts in place, since it will turn under the tension of the spring on the switch parts, the latter will be carried back to the position shown in Fig. 2. As soon as the link 33 passes below the knife edge 130

27, the switch will open with a snap action, as will be readily understood. The switch cannot be closed again, or, at least, it cannot be left closed until the iron has cooled 5 off sufficiently to solidfy the fusible alloy.

It will be seen that I have provided a very simple and self-contained arrangement for automatically cutting off the current from the iron when a dangerous temperature is 10 reached, and while I have described my invention as embodied in concrete form and as operating in a specific manner in accordance with the provisions of the patent statutes, it should be understood that I do not limit 15 my invention thereto, since various modifications thereof will suggest themselves to those skilled in the art without departing from the spirit of my invention, the scope of which is set forth in the annexed claims.

20 What I claim as new and desire to secure by Letters Patent of the United States, is:—

1. An electrically heated flat iron comprising a switch for making and breaking the heating circuit, an operating member therefor biased to the open position of said switch, connections between the member and said switch whereby a quick make and break action of the switch is effected by the movement of the member in opposite directions, 25 means for manually moving the member against its bias to a position to close the switch, and means for holding the member in such position when the temperature is below a predetermined value but releasing it 30 when the temperature rises to said value.

2. An electrically heated flat iron comprising a switch for making and breaking the heating circuit, an operating member therefor biased to the open position of said switch, 40 connections between the member and said switch whereby a quick make and break action of the switch is effected by the movement of the member in opposite directions, and a rotatable element held stationary when 45 the temperature is below a predetermined value arranged to hold the member in closed position, said element being released to effect the opening of the switch when the temperature rises to said value.

50 3. An electrically heated flat iron comprising a quick-make and break switch in the heating circuit, and an element held stationary when the temperature is below a predetermined value for holding the switch 55 in closed position but released to effect the opening of the switch when the temperature rises to said value.

4. An electrically heated flat iron comprising a quick make and break switch in the 60 heating circuit, an operating member therefor manually operated to the closed position of said switch and biased to the open position thereof, and an element held stationary when the temperature is below a predetermined 65 value for holding the member in

closed position against its bias and releasing it to effect the opening of the switch when the temperature rises to said value.

5. An electrically heated flat iron comprising a switch operating member biased to 70 one position, manually operated means for holding the member against the bias to a second position, a quick make and break switch operated to open and closed positions by the movement of said member, and a rotary element for holding the member in closed position when the temperature is below a predetermined value and releasing it to open the switch when the temperature rises to said value. 80

6. An electrically heated flat iron comprising a switch for making and breaking the heating circuit, an operating member therefor biased to the open position of said switch, connections between the member and said switch whereby a quick make and break action of the switch is effected by the movement of the member in the opposite directions, a rotatable element held stationary when the temperature is below a predetermined value arranged to hold the member in closed position, said element being released to effect the opening of the switch when the temperature rises to said value, a cover for said switch mechanism and a member secured to the switch operating member and projecting through the cover for manually closing the switch when said member is pressed into the cover. 90

7. An electrically heated flat iron comprising a quick make and break switch in the heating circuit, a rotary element for holding the switch in closed position and a fusible metal for holding the rotary element stationary when the temperature is below a predetermined value but releasing it to effect the opening of the switch when the temperature rises to said value. 100

8. An electrically heated flat iron comprising a quick make and break switch in the 110 heating circuit, a rotary element for holding the switch in closed position and an inoxidizable fusible metal for holding the rotary element stationary when the temperature is below a predetermined value but releasing it to effect the opening of the switch when the temperature rises to said value. 115

9. An electrically heated flat iron comprising a quick make and break switch in the heating circuit, a rotary element for holding the switch in the closed position and an inoxidizable fusible alloy having a base of a low fusing point metal and a small content of aluminum for holding the rotary element stationary when the temperature is 120 below a predetermined value but releasing it to effect the opening of the switch when the temperature rises to said value. 125

10. An electrically heated flat iron comprising a quick make and break switch in 130

the heating circuit, a rotary element for holding the switch in the closed position and an inoxidizable fusible alloy containing at least 75% zinc and approximately 5% aluminum for holding the rotary element stationary when the temperature is below a predetermined value but releasing it to effect the opening of the switch when the temperature rises to said value.

10 11. An electrically heated flat iron comprising a quick make and break switch in the heating circuit, a rotary element for hold-

ing the switch in the closed position and an inoxidizable fusible alloy composed of 90% zinc, 4% bismuth and 6% aluminum for holding the rotary element stationary when the temperature is below a predetermined value but releasing it to effect the opening of the switch when the temperature rises to said value.

20

In witness whereof, I have hereunto set my hand this ninth day of February, 1921.

EARL H. RICHARDSON.
